UNITED STATES PATENT OFFICE.

WARREN C. SMART, OF KEMP, INDIAN TERRITORY, ASSIGNOR OF ONE-HALF TO WILLIAM H. LAWRENCE, OF STERRETT, INDIAN TERRITORY.

PESSARY.

No. 806,589.

Specification of Letters Patent.

Patented Dec. 5, 1905.

Application filed July 29, 1905. Serial No. 271,803.

To all whom it may concern:

Be it known that I, WARREN C. SMART, a citizen of the United States of America, residing at Kemp, Central District, Indian Territory, have invented certain new and useful Improvements in Pessaries, of which the following is such a full, clear, and exact description as will enable others skilled in the art to which it appertains to make and use the same, reference being had to the accompanying drawings, forming a part hereof.

This invention is an instrument for supporting a falling womb and for medicinally treating a diseased womb; and it consists in certain novel features hereinafter first fully described and then particularly pointed out in the claims.

In the annexed drawings, which fully illustrate my invention, Figure 1 is an elevation of the instrument arranged as a womb-supporter. Fig. 2 is a vertical section of the same, and Fig. 3 is a sectional view showing the instrument arranged to apply medicine to the womb.

The instrument comprises a stem 1 and a base 2, formed integral with or secured to the lower end of the stem, the said base having a concave upper side adapted to fit against and receive the os or apex of the womb. Extending from the edge of the base 2 is a flexible flange or apron 3, which is adapted to rest upon the walls of the vagina, and thereby support the device in position. This wall or flange or apron 3 is provided with a ring or rim 4 at its annular extremity to prevent collapsing and is adapted to be reversed or carried upward, so as to surround the stem and form a large cup, in which may be placed saturated cotton for the purpose of applying medicine to a diseased womb.

When the instrument is to be used to support a falling womb, it is placed in the vagina with the stem entering the mouth of the womb and the concave side of the base fitting against the os. In this position the depending flange or wall 3 will rest lightly upon the walls of the vagina and will bear closely against the same, so that the device will be held in position by atmospheric pressure, as well as by

the muscular action of the surrounding parts and the strain on the patient consequently reduced to a minimum. It will be seen at once that when the instrument is thus arranged in position it will be impossible for the womb to fall. Should it be desired to use the instrument to apply medicine to a diseased womb, the annular flange or apron is reversed, so as to extend up around the stem, and the large cup thus provided is filled with cotton saturated with the proper salve or other remedy. The instrument is then inserted so that the stem will enter the mouth of the womb and the upturned flange or apron will surround the same, fitting between the walls of the uterus and the vagina, so as to bring the medicine into intimate contact with the mouth of the womb.

The device is preferably constructed in one integral body of rubber; but this detail is not essential.

The instrument may be worn without any inconvenience to or strain upon the patient and is obviously efficient.

Having thus described my invention, what I claim, and desire to secure by Letters Patent, is—

1. An instrument of the character set forth comprising a stem, a base from which the stem rises, said base having a concave upper side, and a flexible flange extending from the edge of the base and arranged to depend therefrom to form a supporting-wall or be reversed to extend above the base and form a cup.

2. An instrument of the character set forth comprising a base having a concave upper side, a flexible flange extending from the edge of the base and arranged to depend therefrom or be reversed to extend above the base and form a surrounding cup, and a reinforcing-rim at the annular extremity of the said flange.

In testimony whereof I have signed this specification in the presence of two subscribing witnesses.

WARREN C. SMART.
